(57) **CLAIM**

The ornamental design for a tray for filling of vials, syringes and cartridges for fill and finish machines, as shown and described.

DESCRIPTION

Indication of products No(s) 1-2: Tray for filling of vials, syringes and cartridges for fill and finish machines

Fig. 1.1 is a left side top perspective view of a tray for filling of vials, syringes, and cartridges for fill and finish machines; fig. 1.2 is a top view thereof; fig. 1.3 is a bottom view thereof; fig. 1.4 is a front view thereof; fig. 1.5 is a back view thereof; fig. 1.6 is a right side view thereof; fig. 1.7 is a left side view thereof; fig. 1.8 is a right side top perspective view thereof; fig. 1.9 is a left side bottom perspective view thereof; and fig. 1.10 is a right side bottom perspective view thereof; fig. 2.1 is a left side top perspective view of a tray for filling of vials, syringes, and cartridges for fill and finish machines; fig. 2.2 is a top view thereof; fig. 2.3 is a bottom view thereof; fig. 2.4 is a front view thereof; fig. 2.5 is a back view thereof; fig. 2.6 is a right side view thereof; fig. 2.7 is a left side view thereof; fig. 2.8 is a right side top perspective view thereof; fig. 2.9 is a left side bottom perspective view thereof; and fig. 2.10 is a right side bottom perspective view thereof

The broken lines and the area within the broken lines in the figures of design 2 show portions of the product which form no part of the claimed designs.
